CENTRALIZED TRAFFIC CONTROLLING
SYSTEM

Neil D. Preston, Rochester, N. Y., assignor to General Railway Signal Company, Rochester, N. Y.

Application January 27, 1932, Serial No. 589,186

42 Claims. (Cl. 177—353)

This invention relates to a relay code-type selector system, which is more particularly adapted for controlling the signals, and switch machines of a railway system, and for receiving indications as to the progress of trains, positions of switches, and the like.

This invention is particularly useful in the dispatching of trains on railway systems, as such train dispatching systems on congested railroads are called upon to carry out a large number of control and indication functions during a very short time. By reason of the fact that a single dispatcher can handle the traffic over a large section of track, it becomes apparent that the number of line wires of the system should be reduced to a minimum and at the same time it should be possible to transmit the controls and indications at a sufficiently high rate of speed to avoid the accumulation of stored controls and indications.

With the above and other important considerations in mind, the present invention contemplates the use of a very large variety of distinctive code characters, so that less steps need be taken to obtain the necessary number of distinctive code combinations required. In accordance with the present invention, it is proposed to use three line wires and to employ code creating and code deciphering relays, with the provision of means to condition each of two of these line wires with positive or negative polarity, or de-energize either or both line wires, as a result of which any one of nine different conditions may be impressed on the line circuits. For instance, if one of the line wires is called a line A and the other one is called a line B, while the third line wire is used as a common return for lines A and B, then with the line B deenergized, the line A may be energized (+) or (-), resulting in two distinctive conditions; with the line A deenergized, the line B may be energized (+) or (-), thus giving two more distinctive conditions; and with the line A energized (+) or (-), the line B may be energized (+) or (-), giving four more distinctive conditions, thus resulting in eight distinctive conditions of these lines A and B used for forming code characters. Furthermore, with the line A and line B both deenergized, a ninth condition results, but this ninth condition is used for spacing the above mentioned code characters and for stepping purposes and does not constitute a distinctive code character for transmitting purposes. Obviously, the provision of eight distinctive code characters for each step means that sixty-four distinctive codes

may be obtained where each complete code comprises two steps; and similarly five hundred and twelve distinctive complete codes may be obtained where each complete code comprises three steps. Thus, one purpose of the present invention is to provide a code system which builds up very rapidly as the number of steps are increased, and to accomplish this over a minimum number of line wires.

One feature of the present invention is to so organize the control line circuits with the apparatus at the central office and at the field stations that irrespective of whether the control office is transmitting codes to a field station or whether a field station is transmitting codes to the central office, the same timing apparatus located only in the central office is effective to measure off the time duration of the impulses and the spaces between the impulses. In other words, the central office or any one of the field stations may distinctively energize the line circuits as above pointed out to form eight distinctive code characters for each step, but irrespective of the location of the particular transmitting apparatus for a cycle of operation of the system, the timing of the steps is accomplished in the central office.

This feature has been shown in my later filed copending application Ser. No. 596,516, filed March 3, 1932, in which I am claiming all of the subject matter which is common with this application with regard to the above mentioned feature and its related elements.

Other objects and purposes of the present invention reside in the provision of means whereby indication codes may be transmitted from one of a large number of field stations connected in series to a central office through the medium of a source of current located at the most distant field station.

Another feature of the present invention resides in the provision of means whereby a cycle of operation may be a short cycle for transmitting either control impulses from the central office to a particular way station, or may be a short cycle for transmitting indication impulses from a particular way station to the central office; or a cycle of operation may be a long or tandem cycle, during which the first portion of the cycle transmits distinctive control impulses to a particular way station and during which the second portion of the cycle transmits distinctive indication impulses from the same or a different way station to the central office, there being no period of

hesitation, or blank, between these two portions of the tandem cycle.

Other objects, purposes and characteristic features of the present invention reside in particular interconnections between associated relays to obtain new and peculiar functions which may be used in the other types of selector systems, and the like, which will be apparent from the accompanying drawings and will in part be more particularly pointed out in the description hereinafter.

In describing the invention in detail reference will be made to the accompanying drawings, in which:

15 Fig. 1 shows in a schematic manner the selector system embodying the present invention, with many of the details omitted for convenience;

20 Figs. 2A, 2B, 2C and 2D illustrate one embodiment of the invention in detail with some of the intermediate stations omitted; and

Fig. 3 shows the code tables for a particular control cycle, for an indication cycle and for a tandem cycle.

Structure.—It is believed expedient to first name the various relays and point out briefly the functions that they perform. With the drawings of Fig. 2 arranged end to end it will be noted that the various way stations are connected by three line wires, namely, "line A," "line B" and "common" which is the return wire for lines A and B, and that at the central office and at each way station line A and line B include a three-position polar relay and that the various line relays may be energized from the central office battery 10 and that they also may be energized from any one of the way stations from the battery 11 located in the "end battery control station," this being most clearly shown in Figs. 1 and 2D of the drawings.

40 Referring again to Fig. 1 of the drawings, it will be noted that the control code selecting relays CSA and CSB are located in the central office and are used for determining the character of each combination of pulses on the line wires 45 A and B, namely, (+), (-) or deenergized. Also, it will be noted that the office battery selecting relay OBS is normally deenergized so that it may through its contacts 191 and 192 connect the lines A and B to the central office battery 10 through the contacts 146 and 147 of the control selecting relays CSA and CSB, but when energized connects the lines A and B directly to the common return wire. Also, it should be noted that there is a field station battery selecting relay FBS located in the end battery control station at the extreme end of the system (see Figs. 1 and 2D), and that this station battery selecting relay FBS is normally deenergized and connects the three line wires together, but when energized connects the lines A and B to the battery 11, the mid-point of which is connected to the common return wire. Attention is now directed to the fact that if the relays OBS and FBS are both energized the polar line relays LA⁰, LB⁰ located in the central office CO may be operated to any one of their three distinctive positions in accordance with the condition of energization of the relays CAP, CBP, PAP and PBP at the particular way station 50 where the station selecting and pulsing determining relay LIR is up (see Fig. 2C). The relays CAP and CBP may for convenience be called the "continuity indication code pulsing relays"; whereas the relays PAP and PBP may for convenience be called the "polarity indication puls-

ing relays." It may be pointed out here that these relays CAP, CBP, PAP and PBP can be rendered effective only at one way station at one time, as determined by the lock-in relay LIR.

It will be noted that the various line relays have been designated LA with the proper exponent corresponding to the station in which it is located for those included in the A line, whereas they have been designated LB with the proper exponent when included in the B line. It will be noted that the various line relays are repeated, except for polarity, by repeater relays LAP and LBP containing exponents corresponding to the way station at which they are located, and that these relays have included in series therewith a slow acting relay SR containing an exponent corresponding to the station at which it is located, but this slow acting repeater relay is not connected in series with the repeater relay of the B line, namely, LBP until the slow acting relay has first been picked up by the A line, the purpose of this feature is to maintain the slow acting repeater relay SR deenergized, this relay manifesting the normal condition of the system that the A line is deenergized and the B line is energized.

At the end battery control station, located at the far end of the system (see Figs. 1 and 2D), is an "indication conditioning relay" OT, which becomes energized in the event that an indication is to be transmitted, this irrespective of whether the indication is to be transmitted in a short indication cycle, or whether it is to be transmitted in the second portion of a tandem cycle, and also independently of whether the last or an intermediate station is ready to transmit an indication, and this indication conditioning relay OT is used to energize the field battery selecting relay FBS, the energization of this field battery selecting relay FBS taking place upon the first step of the cycle in the event the cycle is an indication cycle, but is energized on the fourth step of the cycle in the event the indication is to be transmitted during the second portion of a tandem cycle.

Referring now to Figs. 2A, 2B, 2C and 2D of the drawings, the stepping relays in the central office have been designated a, b, c, f, g and h, whereas the companion way station stepping relays have been numbered 1, 2, 3, 6, 7 and 8. It will be noted that the pick-up circuits for these various stepping relays include back contacts 13 and 14 at the central office and back contacts 15 and 16 at the way station of line repeating relays LAP⁰ and LBP⁰ and LAP² and LBP², respectively, from which it is apparent that stepping takes place only when both lines A and B are deenergized. The half-step relays HS⁰ and HS² are employed to keep the stepping relays from successively picking up in rapid sequence in response to the first deenergization of the lines A and B, as interpreted by closure of contacts 13, 14, 15, 16, of relays LAP⁰, LBP⁰, LAP² and LBP², respectively, it being understood that each stepping relay is to pick up upon deenergization of the lines A and B, and the contact 17 of the half-step relay HS⁰ (see Fig. 2B) must be down for all odd numbered stepping relays to pick up and must be up for all even numbered stepping relays to pick up, as is also true of contact 45 of relay HS² (see Fig. 2D).

Referring now to Fig. 2B the impulsing relay IM is the relay that determines the time when both lines are to be opened, that is places the double zero code on a line for the purpose of

stepping the stepping relays in the central office and in the way stations in synchronism, and also determines when the new code character is to be transmitted, this by reclosure of the lines A and B. This relay IM carries out this function of opening and reclosing both lines A and B simultaneously, not only when the code originates in the central office but also if the code originates at any one of the way stations, of which only one has been shown for convenience. In this connection it should be noted that the open condition of one of the lines A or B at a time is accomplished by the contacts of control selecting relays CSA and CSB in their neutral positions insofar as the transmission of a code from the central office is concerned, and that the continuity indication pulsing relays CAP and CBP (see Fig. 2C) perform this function when that particular field station is transmitting a code to the central office. In addition to the slow acting relay SR⁰ in the central office, there is a repeater slow acting relay SRP which repeats the picking up and dropping of the relay SR⁰ after a short interval of time.

In the central office there is also a field starting relay FST and an office starting relay OST, controlled by code determining relay CD¹ which is controlled by the lever change relay LCR¹, the purpose of which is in part apparent and will be more particularly pointed out hereinafter. Similarly, each field station is provided with a normally energized stick change relay CH (see Fig. 2C), which relay CH is normally stuck up through contacts which are momentarily opened by a changed condition at such field station which is to be transmitted to the central office. Each of the way stations is also provided with a relay SE, having an exponent corresponding to the way station, which is picked up if the line A is energized positively during the initiating period of the system, that is, the first changed condition of the lines after the normal period during which the line A is deenergized and the B line is energized with current of positive polarity. With this relay SE (with proper exponent) in the central office and the various way stations picked up, a short indicating cycle is transmitted.

In order to interpret the character of the code not only for a particular step, but for a series of steps, there have been provided in the central office and in each of the way stations polarity code signifying relays A⁰, A², B⁰ and B² which signify the polarity of the lines A and B respectively, during a particular selecting period, similar continuity code signifying relays M⁰, M², N⁰ and N² are provided to signify whether the lines A or B are energized or deenergized during this selecting period. The purpose of these various relays A, B, M and N, containing proper exponents, is to integrate at particular times the condition of polarity and continuity of the lines A and B, and they result in picking up the proper code relays SO-1, SO-2, KO-1 or KO-2, the numeral in these reference characters signifying the digit of the code, so to speak, this because one of these relays, there being eight of the first order, is picked up during the first step, and one of sixty-four code relays of the second order is picked up through a contact on a code relay of the first order during the second step of the cycle, and so on. From this consideration it is apparent that if code relays of two different orders are used, any one of sixty-four way stations may be selected, and that if code relays of the third

order are employed (three steps) five hundred and twelve stations may be selected, as is also true of the number of way station registration relays that may be picked up in the central office from distant way stations. It may be pointed out here that the line repeater relays LAP⁰, LBP⁰, LAP² and LBP² and their associated slow acting relays are energized through the contacts 9, 12, 92 and 115 of relays LA⁰, LB⁰, LA² and LB², respectively.

In the particular embodiment of the invention illustrated, it is assumed that two steps will be employed for selection of stations for the out-bound transmission of controls from the control office, and one step for the transmission of such controls to the particular station selected. Similarly, two steps are used for station registration for in-bound indications, and one step for the transmission of the indications. These three steps provide a station capacity of 64, and 8 distinctive controls or indications for each of these stations. The three stepping relays a, b, and c in the control office (Fig. 2B) and the stepping relays 1, 2, and 3 (Fig. 2D) at each field station, are used to provide the three steps for out-bound station selection and transmission of controls. The three stepping relays f, g, and h in the control office and 6, 7, and 8 at the field stations provide the steps for the in-bound transmission of indications. In other words, in accordance with this invention, the stepping relays for the transmission of controls are arranged in one group, and the stepping relays for the transmission of indications are arranged in another group; and provision is made, in the manner explained more in detail later, so that at the beginning of an operating cycle, the stepping may start with the first group of stepping relays for the transmission of controls, or with the second group for the transmission of indications, depending upon whether or not this operating cycle is to be for controls alone, or for indications alone. In the case that indications are ready to be transmitted at the same time the controls are to be transmitted, the stepping starts with the first group of stepping relays for the transmission of controls, and continues through the second group of stepping relays for the transmission of indications, during the same operating cycle, and without restoring the system to its normal condition of rest, thereby constituting a so-called tandem cycle, during which both controls and indications are transmitted in succession without interruption.

OPERATION

Generally speaking, in assuming the system to be at rest in the normal condition shown, the first phase of the operation involves starting the system into operation whenever new controls or new indications have to be transmitted, and determining whether or not the consequent operating cycle of the system shall be one for the transmission of controls alone, or indications alone or a tandem cycle of both controls and indications. During the initial energization of the line circuits, which may be called the conditioning or initiating period, the polarity of energization of the line A determines whether or not the consequent operating cycle shall involve the transmission of controls, either alone or followed by the transmission of indications in a tandem cycle.

Following this initial conditioning operation, the stepping takes place, during which the lines A and B are selectively energized with either

polarity or deenergized to provide any one of 8 distinctive code impulses for each step, thereby selecting or registering the station, and transmitting the controls or indications, as the case 5 may be. At the end of this stepping operation, which may be either a single cycle of controls or indications, or a tandem cycle of both controls and indications, the system is restored to the normal condition, ready for another operating 10 cycle.

Fig. 3 of the drawings shows typical examples of the way in which the lines A and B are respectively energized or deenergized for a control cycle, for indications, and a tandem cycle, a specific 15 code call for a particular station, and a specific code combination for controls and indications being assumed. It should, of course, be understood that the number of steps illustrated and controls and indications assumed and described, are merely 20 typical and representative of the functioning of the system of this invention. In particular, the following detail description of the operation has been limited to the selection or registration of only one particular station, and the transmission of only one kind of control or indication; and it should be understood, that the system 25 operates to provide in a similar way for the selection or registration of a large number of stations, and the transmission to or from each station of 30 a large number of controls and indications.

Referring to the code tables of Fig. 3, under normal conditions with the system at rest, or in the period of blank, the line A is deenergized, as indicated by the symbol O, and the line B is energized with positive polarity, as indicated by the symbol (+). If new controls are ready to be transmitted prior to the initiation of an operating cycle, the line A is energized with a negative polarity, while the line B is held energized with 40 the positive polarity for station lock-out purposes. If, however, no new controls are ready to be transmitted at the beginning of an operating cycle, initiated from the field, then the line A is energized with positive polarity, while the line B 45 is held energized. These different conditions of the line circuits during the initiating or conditioning period are shown in Fig. 3 for the control cycle and the indication cycle. In the case of an indication cycle, the condition of the line B is indicated by the symbol (O+), because the line B is energized only up to the nearest station ready to send in indications, and is deenergized beyond that station. If the line A is energized 50 (—) for a control cycle, the stepping starts with the first relays *a* and *b* of the group for controls; whereas if the line A is energized with (+), the stepping starts with the first relay *f* and *g* for the second group of stepping relays for the 55 transmission of indications. If at the time an operating cycle is initiated for the transmission of controls, some field station has new indications to transmit, conditions are established so that two groups of stepping relays are operated, without restoring the system to normal, thereby providing a tandem cycle.

With this brief and general statement of the operating principles of the system, the operation will now be described in detail for certain typical controls and indications. Thus, the operation 70 will be described for the case where the lever *L*¹ in the control office is moved from the position shown for the purpose of operating the switch machine control relay SMR at the particular field station shown in Fig. 2D, and for the case where the presence of a train on the detector track 75

circuit having the track relay TR, as shown in Fig. 2D, may be transmitted and indicated in the control office by lighting the lamp I. Following this explanation of the transmission of controls and indications separately, it may then be 5 explained how these typical controls of a switch machine and indication of a track circuit may be transmitted during the same double or tandem cycle.

Cycle of controls alone

10

Referring to Fig. 2A, and assuming the lever *L*¹ to be typical of one of the various levers in the control office operated manually by the operator, upon movement of such lever to a new position, by the operation of a starting button, or equivalent means, a relay LCR¹ is deenergized, this being accomplished in the arrangement shown by opening the stick circuit for this relay through its lower winding at the lever contacts. 20 The relay LCR¹ shown is representative of a series of similar relays associated with the groups of levers belonging to the several stations; and associated with each of these relays is a code determining relay, one of which designated CD¹ 25 for the lever *L*¹ having been shown. These several code determining relays are electrically interlocked, in the manner shown, for example, in the application of W. D. Hailes et al., Ser. No. 526,674, filed March 31, 1931, for the purpose 30 of permitting these code determining relays to be energized only one at a time in a predetermined sequence while the system is at rest. The details of the means for thus enabling controls to be transmitted to stations one at a time as the 35 operator positions the levers to different positions, while preferably employed with the system of this invention, is not material to its operation; and for simplicity, a detail illustration and explanation of this means will not be given.

With the code determining relay CD¹ picked up, an energizing circuit, including a front contact 22 of the relay CD¹ and a back contact 23 of the relay FST, is closed for the office starting relay OST. Picking up of the relay OST opens 45 its interlocked contact 24, thereby preventing further picking up of the field starting relay FST during the same cycle. Picking up of the office starting relay OST closes the following energizing circuit for the control selecting relay CSA:—beginning at the terminal (—) of the central office split battery, back contact 26 of the slow repeater relay SRP, front contact 27 of the office starting relay OST, wire 4, back contacts 28, 29 and 30 of stepping relays *a*, *b*, and *c*, wire 56, back 55 contact 31 of the office starting selecting relay OBS, through the winding of the control selecting relay CSA, to the common return wire C connected to the mid-point of said split battery. Negative energization of the relay CSA causes the line 60 A to be energized by current of negative polarity (this picks up relay LAP² but this relay performs no function at this time), and since the line B is still energized with current of positive polarity the proper current is flowing during the initiating 65 period of the system, namely negative current for line A and positive current for line B, to initiate the system for a control cycle (see table Fig. 3).

When the line circuit A is thus energized with a negative polarity, the polar armature 180 of the line relay LA⁰ in the control office is assumed to move to the left; and while a circuit is closed through the back contact 181 of the relay SR⁰, wire 182 (see Fig. 2A) through the upper winding of the selecting relay SE⁰ (see Fig. 2B), this relay 75

is not energized, since its coil is connected to (—). Similarly, the relays as SE^2 , at the several field stations are not energized. Consequently, the stepping starts with the first relays a and l of the group for transmission of controls.

The energization of the line A with either polarity establishes a circuit through the contact finger 9 of the line relay LA^0 for energizing the slow-release relay SR^0 in series with the relay LAP^0 ; and after a short time, this slow-releasing relay SR^0 attracts its armature and closes its front contact 44 to energize the slow-releasing repeater relay SRP . Similarly, at each field station a slow-releasing relay such as SP^2 , is energized. These slow-releasing relays maintain their armatures attracted during the impulsion of the line circuits throughout the operating cycle.

The energization of the slow-releasing relay SR^0 in the control office breaks at its back contact 277 the pick-up circuit for the code determining relay CD^1 , leaving this relay held up by a stick circuit through its front contact 19 , which is broken at the back contact 21 of the stepping relay c . The relay LCR^1 is likewise restored to its energized condition on this last step in the particular simplified arrangement shown, it being assumed that this relay LCR^1 will pick up quicker than the relay CD^1 will drop.

The energization of the slow-releasing repeater relay SRP in the control office marks the end of the conditioning or initiating period, after which the system alternately deenergizes both lines A and B to take a step, and energizes the lines A or B, or A and B, with selected polarities to provide the code combinations of impulses for the selection of stations and transmission of controls, this stepping operation and transmission of controls being hereinafter explained more in detail.

Both lines A and B are opened after the conditioning period to take the first step by energizing the impulsion relay IM over a circuit through the front contact 36 of the slow-releasing repeater relay SRP , wire 37 , contact 105 of the relay HS^0 in the lower position, lower winding of the relay IM and through the series of back contacts 113 , 112 , 111 , 106 , 109 , 108 , and 107 of the stepping relays a — c and f — h . The energization of the relay IM opens both lines A and B at its back contacts 38 and 39 . The deenergization of both lines A and B simultaneously, which in a sense may be said to be a zero-zero code, is the condition for stepping.

With the lines A and B both open, the line relays LA^0 , LA^2 , LB^0 and LB^2 all assume their pendent or deenergized positions, thereby causing deenergization of the line repeater relays LAP^0 , LAP^2 , LBP^0 and LBP^2 , thereby causing simultaneous closure of contacts of these relays, namely, contacts 13 and 14 in the central office and contacts 15 and 16 at the way station (see Fig. 2C), and thereby resulting in the simultaneous completion of the following two circuits: (1) beginning at the terminal (+), front contact 44 of the relay SR^0 , back contact 13 of the relay LAP^0 , back contact 14 of the relay LBP^0 , wire 18 , back contact 17 of the relay HS^0 , back contacts 41 , 42 and 43 of relay h , f and b , respectively, winding of the relay a to the other terminal (—), and (2) beginning at the terminal (+) of a way station battery, (this circuit being present at each way station), front contact 35 of the relay SR^2 , back contact 15 of relay LAP^2 , back contact 16 of relay LBP^2 , wire 126 , back contact 45 of

relay HS^2 , back contacts 46 , 47 and 48 of stepping relays 8 , 6 and 2 , respectively, at each of the way stations (see Fig. 2D, for example) through the winding of stepping relay l to the other terminal (—). The relays a and l are then stuck up through their respective stick circuits readily traced and including their respective stick contacts 44 and 49 . The stepping relay l is thus conditioned to transmit the code condition of the next step to the various code signifying relays A^2 , B^2 , M^2 and N^2 .

Picking up of the stepping relay a breaks the circuit for the impulsion relay IM at the back contact 113 of relay a , but since this relay IM is a neutral relay, and therefore slightly slow acting, it will not close its back contacts 38 and 39 until the control selecting relays CSA and CSB are energized to effect the next code character. The relay IM is thus the relay that determines the rate of stepping of the system. It should also be noted that for the particular code applicant has picked to select the way station illustrated, only three code jumpers 50 , 51 and 52 (see Fig. 2A) are employed, this because the second station selecting code character includes a zero code (see "control cycle" Fig. 3).

Bearing in mind that the code determining relay CD^1 for the lever L^1 is energized, and noting that certain of the code determining jumpers 50 , 51 and 52 have been placed in position to select a certain code, the control selecting relays CSA and CSB are energized to one polarity or the other or deenergized, as the case may be, through the following circuits: (1) beginning at the terminal (—) (See Fig. 2A), jumper 51 , front contact 53 of the code determining relay CD^1 , wire 54 , front contact 28 of stepping relay a , back contacts 29 and 30 of stepping relays b and c , wire 56 , back contact 31 of relay OBS through the winding of control selecting relay CSA , to common return wire C connected to the mid-point of the central office battery, and (2) starting at the (—) terminal of the central office battery, jumper 52 , front contact 58 of the relay CD^1 , wire 59 , front contact 60 of the stepping relay a , back contacts 61 and 62 of the stepping relays b and c , wire 63 , back contact 64 of the relay OBS , through the winding of the control selecting relay CSB , to the common return wire C connected to the mid-point of the central office battery. Relay IM now closes its contacts 38 and 39 . It is thus seen that the first station selecting code is (—) for line A and (—) for line B, as indicated in the "control cycle" column of Fig. 3 of the drawings.

Let us now observe what effect this first station selecting code character has upon the apparatus shown in Fig. 2D of the drawings. With the line relays LA^2 and LB^2 (see Fig. 2C) both energized toward the left, and the contact 66 of relay LA^2 toward the left, current of negative polarity is applied to the polarity code signifying relay A^2 , through the following circuit: beginning at the terminal (—) of a suitable field station battery, contact 66 of relay LA^2 , front contact 32 of the slow relay SR^2 , wire 67 , back contact 68 of the stepping relay 3 , front contact 69 of the stepping relay l , through the winding of the relay A^2 , which is one of the two-position polar magnetic stick or stay-where-put type, thus energizing this relay toward the left. Simultaneously with this energization of the relay A^2 , the relay B^2 is energized to the left through the following circuit: beginning at the terminal (—) of the way station battery, polar contact 70 of

the relay LB² toward the left, wire 71, back contact 72 of the stepping relay 3, front contact 73 of the stepping relay 1, through the winding of the relay B², thus operating this stay-where-put relay B² to its left-hand position.

Also, with the lines A and B both energized the line repeater relays LAP² and LBP² are energized, so that the continuity code signifying relays M² and N² are energized as follows: (1) beginning at the terminal (+), front contact 75 of the relay LAP², front contact 76 of the relay LBP², wire 77, back contact 78 of the stepping relay 3, front contact 79 of the stepping relay 1, through the winding of the relay M², to the common return wire C connected to the midpoint of the way station split battery, and (2) beginning at the terminal (+), front contact 80 of the relay LBP², wire 81, back contact 82 of the stepping relay 3, front contact 83 of the stepping relay 1 through the winding of the relay N², to the common return wire C.

The relays A² and B² have thus been energized toward the left and the relays M² and N² have been energized toward the right, so that, with the relay HS² now energized through front contact 116 of relay 1, and with contacts 75 and 76 of relays LAP² and LBP² down, as will be the case when the relay IM is energized for the stepping relays to take their second step, the following circuit for the code relay SO-1 is closed:—beginning at the terminal (+), contact 85 of the relay N² to the right, contact 86 of the relay M² to the right, contact 87 of the relay B² toward the left and contact 88 of the relay A² to the left, code jumper 89, lowering winding of the relay SO-1, front contact 90 of the stepping relay 1, back contact 91 of the stepping relay 2, front contact 93 of the half-step relay HS², wire 94, back contact 76 of the relay LBP², deenergized, and contact 75 of relay LAP² deenergized, to the terminal (-). The relay SO-1 is thus picked up during the next stepping period, namely when both lines A and B are deenergized. With code relay SO-1 once picked up it is stuck up through its stick contact 57 and front contact 35 of relay SR² in series. The code relay SO-1 has thus been picked up in response to the A—, B—code character transmitted during the first station selecting code.

We have already briefly mentioned the second stepping period, namely, the period with the line A and line B both deenergized, but let us now observe how this deenergization of the lines A and B took place. Referring to Fig. 2B it will be noted that the half-step relay HS⁰ was energized in response to the application of the A—, B—code character during the first station selecting code period, because of closed contacts 95 and 96 of line repeater relays LAP⁰ and LBP⁰, respectively, effecting closure of the following circuit:—beginning at the terminal (+), front contact 97 of the stepping relay a, back contacts 98, 99, 100, 101 and 102 of stepping relays b, c, f, g and h, respectively, upper winding of the relay HS⁰, wire 94, through the contacts 95 and 96 in multiple, to the common return wire C. The closure of this circuit effected energization of the half-step relay HS⁰, thereby closing its front contacts 103, 104 and 105. Closure of the contact 104 caused the relay HS⁰ to be stuck up through a stick circuit including this contact 104 and the front contact 40 of the slow relay SR⁰ (see Fig. 2A), and lifting of the contact 105 closes the following circuit for the upper wind-

ing of the impulsing relay IM to effect opening of the lines A and B: beginning at the terminal (+), back contacts 107, 108, 109, 106, 111 and 112 of relays h, g, f, SE⁰, c and b, respectively, then through front contact 113 of stepping relay a through the upper winding of the impulsing relay IM, through front contact 105 of relay HS⁰, wire 37 and through front contact 36 of relay SRP to the other terminal (-), thus resulting in the opening of the lines A and B for accomplishing the second stepping operation.

With the lines A and B now both deenergized, the second stepping period of the control cycle takes place, this occurring simultaneously with the integration of the code character resulting in picking up of the relay SO-1, (see control cycle table Fig. 3) and the stepping relay b is picked up through the following circuit: beginning at the terminal (+), front contact 44 of the relay SR⁰ (see Fig. 2A), back contacts 13 and 14 of relays LAP⁰ and LBP⁰, wire 18, front contact 17 of half-step relay HS⁰, back contacts 143, 144 and 145 of relays g, SE⁰ and c, front contact 114 of the relay a, winding of the relay b, to the other terminal (-). With this relay b picked up it is stuck up through a stick circuit including its stick contact 74 and front contact 40 of relay SR⁰. A similar circuit is closed for the stepping relay 2 (see Fig. 2D) through the following elements, the relay HS² having in the meantime been picked up through front contact 116 of stepping relay 1, and back contacts 117, 118, 119, 120 and 121 of relays 2, 3, 6, 7 and 8, and through front contacts 122 and 123 in multiple of relays LAP² and LBP²: beginning at the terminal (+) of way station battery (see Fig. 2C) front contact 35 of the relay SR² (see Fig. 2C), back contacts 15 and 16 of relays LAP² and LBP², wire 126, front contact 45 of relay HS², back contacts 127, 128 and 129 of relays 1, SE² and 3, respectively, front contact 130 of stepping relay 1, winding of the stepping relay 2 to the terminal (-). With relay 2 once picked up it will be stuck up through a stick circuit including its stick contact 84 and front contact 35 of relay SR². Stepping relays b and 2 are now energized, so that the second station selecting code character may be transmitted.

This second station selecting code character is applied to the control selecting relays CSA and CSB through the following circuits: (1) beginning at the terminal (+), jumper 50 (see Fig. 2A), front contact 132 of the code determining relay CD¹, wire 133, front contact 29 of the stepping relay b, back contact 30 of the stepping relay c, wire 56, back contact 31 of the relay OBS, winding of the control selecting relay CSA to the common return wire C, and (2) the circuit for the control selecting relay CSB is open, because this circuit includes the contact 135 of the code determining relay CD¹, and since this wire has no code determining jumper in it, the line B will be deenergized during this second station selecting period, during which the line A is energized by current of positive polarity, as indicated in the control cycle column of Fig. 3 of the drawings, this because the relay IM has been dropped in the meantime by lifting of contact 112 of the relay b.

Let us now observe what effect the positively energized condition of line A and the deenergized condition of line B has on the apparatus of the way station, shown in Figs. 2C and 2D. With the line relay LA² energized to the right, the polarity

code signifying relay A² will be energized to the right through the following circuit: beginning at the terminal (+), polar contact 66 of the relay LA² to the right, front contact 32 of the relay 5 SR², wire 67, back contact 68 of the stepping relay 3, front contact 69 of the stepping relay 1, this stepping relay being stuck up until the end of the cycle, winding of the relay A², to the common return wire C. The polarity code signifying relay B² is not operated at this time because the line relay LB² assumes its neutral deenergized condition. The continuity code signifying relay M² is not changed during this second 10 station selecting period because this energizing 15 circuit is broken at the front contact 76 of the relay LBP², but the continuity code signifying relay N² is operated to the left through the following circuit: beginning at the terminal (-), front contact 136 of the relay LAP², back contact 20 80 of the relay LBP², wire 81, back contact 82 of stepping relay 3, front contact 83 of stepping relay 1, through the winding of N² to the common return wire C. With the relay A² now energized to the right and the relay N² now energized to the left, the code relay SO-2 is energized 25 during the next or third stepping period through the following circuit: beginning at the terminal (+), contact 85 of the relay N² to the left, contact 138 of the relay A² to the right, 30 jumper 139, front contact 140 of the code relay SO-1, lower winding of the code relay SO-2, front contact 141 of the stepping relay 2, back contact 142 of the stepping relay 3, back contact 93 of the half-step relay HS², wire 94, and 35 back contacts 76 and 75 of relays LBP² and LAP², respectively, to (-). Relay SO-2 is then stuck up through a stick circuit including its stick contact 65, wire 125, and front contact 35 of relay SR². 40 Attention is directed to the fact that the circuit just traced includes back contact 93 of the relay HS². This relay HS² was actuated to its retracted position during the transmission of the second station selecting code immediately following the picking up of the stepping relay 2 by reason of the closure of the following circuit: 45 beginning at the terminal (-) of the field station battery, front contact 151 of relay HS², front contact 117 of the stepping relay 2, back contacts 118, 119, 120 and 121 of the stepping relays 3, 6, 7 and 8, respectively, upper winding of the half-step relay HS² and through front contact 122 of the line repeater relay LAP² to the common return wire C connected to the mid-point of said field station battery. The closure of the circuit for the upper winding of relay HS² just traced applies a current neutralizing the effect of the current in the lower winding in this relay HS², so that the relay HS² assumes its deenergized position, opening its two stick contacts 150 and 151, so that this relay HS² now remains deenergized until it is again picked up by current flowing from right to left through its upper winding, which occurs with the stepping relay 3 energized and one, the other or both of the relays LAP² and LBP² energized. In this connection it should be remembered that the stepping relays 1 and 2 both remain stuck up, as is also true of the remaining stepping relays until the end of 50 the code cycle.

The above description points out the manner of selection of channel circuits for energization in response to the station selection coded impulses. These channel circuits which are connected to code signifying relays A², B², M² and

N² are closed by the picking up of relay 1 and opened by the picking up of relay 3. Since relay 3 is picked up before the operation of any stepping relay which operates in response to the indication portion of a tandem cycle (later explained), it will be apparent that any energy applied to conductors 67, 71, 77 and 81 by the operation of relays LA², LB², LAP² and LBP² by the conditioning of the line circuits during the transmission of indications in a tandem cycle, 10 will be ineffective to change the positions taken by these code signifying relays during the control portion of a tandem cycle. 15

Referring again to the table in Fig. 3, it should be remembered that the second station selecting 20 character of plus on the line A and with the line B open has been transmitted, and that the next operation is a stepping period during which both the line A and the line B are deenergized. This is accomplished, referring to Fig. 2B, by dropping 25 of the half-step relay HS⁰ in the central office, and its shifting of the contact 105 from its attracted to its retracted position. This relay HS⁰ is retracted by closure of the following bucking circuit: beginning at the terminal (-) of the 30 central office battery, front contact 152 of the relay HS⁰, front contact 98 of the stepping relay b, back contacts 99, 100, 101 and 102 of stepping relays c, f, g and h, respectively, upper winding of the relay HS⁰, wire 94, through the front contact 95 of the relay LAP⁰, to battery connection C. This relay HS⁰ now drops by reason of the bucking action of its two energized windings, and upon dropping opens its two stick contacts 35 104 and 152, for reasons already explained in connection with the relay HS². Shifting of the contact 105 of relay HS⁰ from its attracted to its retracted position completes the following energizing circuit for the lower winding of the impulsive relay IM: beginning at the terminal 40 (+), back contacts 107, 108, 109, 106 and 111 of relays h, g, f, SE⁰ and c, respectively, front contact 112 of the relay b, lower winding of the relay IM, back contact 105 of the relay HS⁰, wire 137, and front contact 36 of the slow repeater 45 relay SRP, to (-).

Picking up of the impulsive relay IM opens both the line A and the line B, thereby causing a stepping operation to take place during which the stepping relays c and 3 are picked up through 50 the following circuits: (1) front contact 44 of the relay SR⁰ (see Fig. 2A), contacts 13 and 14 (retracted) wire 18, contact 17 (retracted) contacts 41 and 42 (retracted) front contact 43 of relay b, winding of the relay c, and (2) front contact 35 of relay SR² (see Fig. 2C), contacts 15 16 (retracted) wire 126, contacts 45, 46 and 47 (all retracted), front contact 48 of the stepping relay 2, through the winding of the stepping relay 3 to the other terminal (-). The completion of 60 these two circuits causes the stepping relays c and 3 to be picked up and stuck up through their stick contacts 153 and 154, respectively. Picking up of the stepping relay c closes the following energizing circuit for the control selecting relay CSA:—beginning at the terminal (-), contact of lever L¹ (see Fig. 2A), front contact 148 of the code determining relay CD¹, wire 155, front contact 30 of the stepping relay c, wire 55 56, back contact 31 of relay OBS, winding of the 65 control selecting relay CSA to the common return wire C. Relay IM now drops for obvious reasons allowing the contacts 146 and 147 of relays CSA and CSB to transmit their code character. 70

Since the wire leading from front contact 62 of the stepping relay *c* is not connected to any source of current, the line B will be deenergized during this control code selecting period, so that 5 the line A will be energized by current of negative polarity and the line B will be deenergized, as signified by the code table in Fig. 3 of the drawings. With the relay LA² now energized toward the left the polarity code signifying 10 switch machine control relay SMR will be energized through the following circuit: beginning at the terminal (—), contact 66 of the relay LA² to the left (see Fig. 2C), front contact 32 of the relay SR², wire 61, front contact 68 of the 15 stepping relay 3, front contact 156 of the code relay SO—2, through the winding of the switch machine control relay SMR, to the common return wire C connected to the mid-point of the way station battery. The closure of the circuit 20 just traced operates the relay SMR to the left and completes the reverse circuit for the switch machine SM, thereby operating this switch machine to its take-siding position.

Referring now to Figs. 2A and 2B, attention is 25 directed to the fact that relay IM is picked up to terminate the control code which deenergizes relays LA⁰ and LAP⁰. This effects the energization of the office battery selecting relay OBS through the following circuit: beginning at the 30 terminal (+) of the central office battery, front contact 44 of the relay SR⁰ (see Fig. 2A), back contact 13 of relay LAP⁰, back contact 14 of relay LBP⁰, wire 18, front contact 17 of relay HS⁰, back contacts 143 and 144 of stepping relays *g* 35 and SE⁰, front contact 145 of stepping relay *c*, wire 157, winding of the relay OBS, wire 158, front contact 159 of the impulsing relay IM to the other terminal (—). With this relay OBS once picked up, it is stuck up through a stick circuit 40 including its stick contact 137. The stepping relay *f* is picked up in multiple with relay OBS which results in dropping of the relay IM due to contact 109 of relay *f*. Relay 6 at the station is picked up over an obvious circuit through back 45 contacts 15 and 16. However, with relay OBS energized and relay FBS deenergized, the lines A and B cannot be energized from either end. Picking up of the office battery selecting relay OBS will of course cut off the control formerly 50 effected by the relays CSA and CSB, so that the lines A and B can no longer be energized from the central office, and since the relay OT (see Fig. 2D) was not energized during the initiating period of the cycle under consideration, as is obvious 55 from the pick-up circuit for this relay OT, the station battery selecting relay FBS (see Fig. 2D) will not be picked up, so that the lines A and B cannot be energized from either end of the system. Under this condition it is obvious 60 that after an interval of time the slow acting relays SR⁰ and SR² (see Figs. 2A and 2C) will assume their retracted positions, and a short period of time thereafter the slow repeater relay SRP (see Fig. 2A) will also assume its deenergized retracted position.

Dropping of the slow acting relays SR⁰ and SR², will of course effect deenergization of relay OBS, the stepping relays *a*, *b*, *c*, *f*, and 1, 2, 3, 6, which were formerly stuck up through front contact 40 of relay SR⁰ and front contact 35 of relay SR², respectively. With the stepping relay *a* now assuming its retracted position, and also with the office battery selecting relay OBS deenergized, the control selecting relay CSB is 70 returned to its normal right-hand position

through its normal circuit, heretofore traced, and briefly comprising back contacts 60, 61, and 62 of relays *a*, *b* and *c*, wire 63, and back contact 64 of relay OBS, so that the system is now returned to its original and normal condition, in which the line B is energized by current of positive polarity and the line A is deenergized. It is of course understood that the picking up of the stepping relay *c* (contact 21) closed a pick-up circuit for the lever relay LCR¹, and broke the stick circuit for the relay CD¹, so that these relays LCR¹ and CD¹ have been returned to their normal condition. Contact 149 of relay CD¹ is employed so that relay LCR¹ can only be picked up when relay CD¹ is up. 15

In the same manner as just explained, with both lines A and B deenergized for a sufficient period of time to deenergize relay SRP, the deenergization of relay SR² will be effected, so that the relays 1, 2, 3, 6, SO—1, and SO—2 are returned to their normal deenergized conditions. Also, it should be understood that the simultaneous energized condition of relays SO—1 and SO—2 signifies a particular station selecting code and results in the circuit through the contact 25 156 of relay SO—2 being complete at that point, so that a specific code character may be transmitted to that particular field station through said contact.

Briefly summarizing in general terms this operation of the transmission of controls alone, above described in detail, the manipulation of the levers or the like by the operator in the control office results in the energization of a particular code determining relay such as CD¹, which in turn energizes the relay OST for a control office start. This brings about the energization of the normally de-energized line A with (—) polarity, which fails to pick up the selecting relays SE in the control office and at the several field stations, with the result that the stepping operation starts with the group of relays for transmission of controls. The slow-releasing relays are energized in the control office and at each field station to indicate the beginning of an operating 45 cycle, these relays being maintained energized throughout the operating cycle, on account of their slow-releasing characteristics, notwithstanding the momentary de-energization of the line circuits during the stepping operation. 50

After this conditioning or initiating period, both lines A and B are simultaneously opened by the impulsing relay IM to pick up the first stepping relay *a* in the control office and the corresponding first relay 1 at the field stations. With the first stepping relay *a* in the control office energized, the three position polar relays CSA and CSB (Fig. 2A) controlling the polarity of energization of the lines A and B respectively, or their de-energized condition are connected, 60 through code buses 54 and 59 and through contacts on the particular code determining relay CD¹ then energized, to code jumpers 51 and 52 by means of which these relays CSA and CSB may be respectively energized with either polarity or de-energized, depending upon the code call for the particular station to which the controls are to be transmitted. For example, in the specific case assumed, the code jumpers 51 and 52 are positioned so that the relays CSA and 70 CSB are both energized with a negative polarity, which in turn connects the control office battery 10 to the lines A and B so as to apply a (—) impulse to both lines, as indicated in the table of codes in Fig. 3. This particular code 75

impulse combination of (—) (—) is, of course, only one of the 8 different combinations which may be applied to the lines A and B after the first step.

- 5 The energization of the first stepping relay *a* in the control office results in the de-energization of the impulse relay IM, which closes the lines A and B, so that these lines will be energized in accordance with the code call. This energization 10 of the lines A and B is in turn followed by another operation of the impulse relay IM, thereby causing a second stepping relay of the control group in the control office and each field station to pick up. This shifts the connections to the relay CSA 15 and CSB to another pair of code buses which similarly may be respectively energized with either polarity or de-energized to provide any one of 8 different code combinations. As a result of these two station selecting steps a relay SO-2, 20 corresponding to the particular code call being transmitted, is energized at one of the field stations. In this connection it should be understood that a plurality of these code-responsive relays for station selection may be used at one location, 25 and operated by the same apparatus, the particular code call to which each of these relays as SO-2 responds being determined by the position of the code jumpers as 89 and 139.

Following the selection of the station being 30 called, on the next or third step, a code combination for the desired control may be transmitted. Any one of 8 different control conditions may be transmitted on this third step, which may be used to control switches or signals in any desired way 35 and if necessary, any one of 8 other different control conditions may be transmitted on another step, and so on. To avoid complications in the illustration and description, no attempt has been made to show how these control codes may be 40 utilized to govern traffic, the operation of a switch machine as shown and described, being sufficient to make clear how the system may be applied as desired, to varying operating conditions.

However, the present disclosure sets forth more 45 particularly how any two of four different control conditions may be transmitted on this third step, which control conditions may be used to control switches, signals or the like. More specifically, the polarity of the A line may be determined in accordance with one control lever to 50 control a two-position relay such as relay SMR, as above described; and similarly, the polarity of the B line may be determined in accordance with the position of another lever to thereby control 55 another two-position relay, similar to relay SMR. In other words, two two-position magnetic stick type control relays, such as relay SMR, may be controlled on each step in accordance with their respective levers after the station is selected. 60 Although only the control for relay SMR has been shown, it is believed sufficient to point out that a relay similar to relay SMR for the third step may be connected to the front point of contact 72 of stepping relay 3 through a front contact of the 65 relay SO-2 similar to the relay SMR, and also that similar control is provided for each pair of control relays for the succeeding steps when a greater number of control steps is employed. To 70 avoid complication in the illustration and description, no attempt has been made to show how these control relays may be utilized to govern traffic, the operation of a switch machine from relay SMR, as shown and described being sufficient to make clear how the system may be applied to vary the 75 traffic operating conditions.

After the energization of the lines A and B, following the third step, and when the lines A and B are both broken by the impulsing relay IM, the relay OBS in the control office is energized, connecting the lines A and B together and to the 5 common wire. In the case of a cycle for the transmission of controls alone as assumed, the line circuits A and B are thus deenergized, notwithstanding the dropping of the impulse relay IM, whereupon the slow-releasing SR relays drop, 10 and the system is restored to the normal condition of rest, ready for another operation.

Indication cycle (in-coming).—Let us now observe how the entrance of a train upon the detector track circuit containing the track relay 15 TR (see Fig. 2D) is able to initiate an indication cycle and will result in the illumination of the indicating lamp I in the central office (see Fig. 2A). Referring to Fig. 2D, dropping of the contact 160 of the track relay TR will result in 20 momentary opening of the stick circuit for the lower winding of the change relay CH including the wire 164 and stick contact 161. The momentary breaking of this stick circuit will effect de-energization of the relay CH, this because the 25 front contact 162 of the indication station selecting pulsing determining relay LIR² is open at this time. Dropping of the change relay CH closes the following circuit for the continuity indicating pulsing relay CBP²: beginning at the back contact 30 35 of the relay SR² (see Fig. 2C), back contact 165 of the relay LAP², back contact 166 of the change relay CH, back contact 34 of the relay SR², through the lower winding of the relay CBP² to the other terminal (—) of the battery. With 35 the relay CBP² picked up, it will be stuck up through its stick circuit including the back contact 172 of the stepping relay 6, back contact 173 of the stepping relay 1, wire 175, winding of relay CBP², and the stick contact 174 of this same relay. 40 Closure of this circuit and the picking up of the relay CBP² effects the opening of the line B at back contact 177 and de-energization of the line repeater relay LBP⁰ in the central office (see Fig. 2A), thereby closing its back contact 167, 45 resulting in closure of the following circuit for the field starting relay FST: beginning at the terminal (+), back contact 167 of the relay LBP⁰, back contact 168 of the relay SRP, back contact 24 of the office starting relay OST, winding of the 50 field starting relay FST, to the other terminal (—).

The relay FST, if once picked up, will be stuck up through its front contact 169 and the front contact 40 of the relay SR⁰ as soon as this slow 55 acting relay SR⁰ picks up, which will happen a little later. Picking up of the field starting relay FST will prevent the picking up of the relay OST thereafter, and will close the following energizing circuit for the control code selecting relay CSA: 60 beginning at the terminal (+) of the central office battery, back contact 170 of the relay SRP, front contact 171 of the relay FST, back contact 27 of the relay OST, wire 4, back contacts 28, 29 and 30 of the stepping relays *a*, *b*, and *c*, wire 56, 65 back contact 31 of the relay OBS to the control code selecting relay CSA, the other side of which is connected to common return wire C.

With the line A now energized by current of positive polarity (as indicated in the initiating 70 period of the indication cycle, see Fig. 3), the front contact 176 of the line repeater relay LAP² (see Fig. 2C) is closed, thereby reclosing the line B through the medium of the upper winding of the station selecting and pulsing deter- 75

mining relay LIR², the contact 177 of the continuity code impulsing relay CBP² now being in its raised position. The completion of the circuit picks up the relay LIR², and with it once picked up it will be stuck up through its stick circuit including its front contact 178 and the front contact 35 of the slow acting relay SR². Also, this picking up of relay LIR² results in reenergization of the relay CH, this through front contact 162 of relay LIR². It is thus seen that the initiating period of the indication cycle constitutes plus polarity for the A line and zero followed by plus polarity for the line B, as indicated at the initiating point in the "indication cycle" column of Fig. 3 of the drawings.

It should be noted that the relay LIR² cannot be picked up unless the relay CBP² has its front contact 177 closed, and further that the relay CBP² cannot be picked up unless the relay SR² has its contact 34 down unless the relay LIR² is already up and has its front contact 202 closed. For this reason the relay LIR² can only be picked up during the initiating period of a cycle, and since during an initiating period the relay CBP can only pick up if the change relay CH is down the relay LIR² picks up only during a cycle in which indications can be transmitted, namely a tandem cycle or an indication cycle.

It is desired to point out here that during the initiating period of the indication cycle, which consisted of plus energization of the line A and deenergization followed by plus energization of the line B the relays SE⁰ (see Fig. 2B) and SE² (see Fig. 2D) were picked up through the following pick-up circuits: (1) starting with the terminal (+) at the central office, contact 180 of the line relay LA⁰, back contact 181 of slow acting relay SR⁰, wire 182, upper winding of the relay SE⁰ to the other terminal (-), and (2) (+) contact 66 of the relay LA² to the right (see Fig. 2C), back contact 32 of the relay SR², wire 188, upper winding of the relay SE², to the other terminal (-). These indication-only selector relays SE⁰ and SE², if once picked up, will stick up through their stick circuits including their stick contacts 183 and 184 respectively, which in turn are connected through front contacts 40 and 35 of relays SR⁰ and SR², respectively, to the plus side of the battery. It may be pointed out that these relays SE⁰ and SE² are only energized if an indication alone is to be transmitted, that is not energized for a "control cycle" and are not energized for a "tandem cycle," and these relays result in causing the stepping relays f and 6 to be picked up first, that is, the relays a, b and c and stepping relays 1, 2 and 3 remain deenergized during an indication cycle.

Also, it should be remembered that during the initiating period the line B was for a time deenergized and was then energized by current of positive polarity. The momentary condition of line A energized and line B deenergized completed the following pick-up circuit for the relay OT located only at the last station namely in the "End Battery Control Station":—beginning at the terminal (+), back contact 35 of the relay SR², front contact 165 of the relay LAP², back contact 175 of the relay LBP², wire 179, winding of the relay OT, to the other terminal minus.

Picking up of the relay SE⁰ (see Fig. 2B) effected closure of the following energizing circuit for the upper winding of the relay HS⁰ during the initiating impulse of the indicating cycle:—beginning at the terminal (+), front

contact 187 of the relay SE⁰, back contacts 100, 101 and 102 of relays f, g and h, upper winding of the relay HS⁰, wire 94, and front contact 95 of the relay LAP⁰. With the relay HS⁰ once picked up it will of course be stuck up for reasons heretofore given. In the same manner as just explained in connection with relay SE⁰, the relay SE² (see Fig. 2D) through the picking up of its contact 190, closes an energizing circuit for the relay HS², which circuit may be traced as follows: beginning at the terminal (+), contact 190 of the relay SE², back contacts 119, 120 and 121, respectively, of relays 6, 7 and 8, upper winding of the half-step relay HS², wire 124, and through front contact 122 of the line repeater relay LAP², to the common return wire C connected to the mid-point of the way station battery.

After a short period of delay following the energization of the slow acting relay SR⁰ (see Fig. 2A) in the central office, a slow repeater relay SRP is energized, thereby closing its contact 36 and effecting energization of the impulsing relay IM (see Fig. 2B) through the upper winding, which results in opening its contacts 38 and 39 to constitute a stepping code.

With relays HS⁰ and HS² now energized and with the relays SE⁰ and SE² now energized the stepping relays f and 6 are energized through the following respective circuits: (1) beginning at the terminal (+), front contact 44 of the relay SR⁰ (see Fig. 2A), back contacts 13 and 14 of line repeater relays LAP⁰ and LBP⁰, wire 18, front contact 17 of relay HS⁰, back contact 143 of relay g, front contact 144 of relay SE⁰ and winding of relay f to (-) and (2) beginning at the terminal (+) of the way station battery, front contact 35 of the relay SR² (see Fig. 2C), back contacts 15 and 16 of the line repeater relay LAP² and LBP², wire 126, front contact 45 of the relay HS², back contact 127 of the stepping relay 7, and front contact 128 of the stepping relay SE², through the winding of the stepping relay 6, to the other terminal (-) of the way station battery.

With the relay SE⁰ now energized as heretofore explained, the office battery selecting relay OBS is energized as soon as the relay IM (see Fig. 2B) is up through the following circuit:—beginning at the terminal plus, now connected to the left hand terminal of relay f as above traced, wire 151, winding of the relay OBS, wire 158 and front contact 159 of the relay IM, (-). It should be noted that the picking up of relay SE⁰ results in the immediate picking up of relay HS⁰ through contact 187 of relay SE⁰ and that relay IM is picked up as soon as relays SE⁰, HS⁰ and SRP are up, namely through contacts 106, 105 and 36, respectively, of these relays. It has just been pointed out that the stepping relay 6 was picked up during the first stepping period and it should be noted that there is a branch circuit to energize the field battery selecting relay FBS. This branch circuit leads from the left terminal of relay 6 and passes through front contact 260 of the relay OT, so that the relay FBS is picked up with the relay 6 and is then stuck up through its stick contact 262 and contact 35 of relay SR².

The first stepping relays of the indication portion of the system, namely the stepping relays f and 6 are now energized, and stuck up through their respective stick contacts 98 and 276, and the system is placed in condition for

transmitting the first station registration impulse from this particular way station to the central office, it being understood that the office battery selecting relay OBS was picked up in response 5 to the picking up of the relay SE⁰, as already explained.

With the stepping relay 6 now energized (see Fig. 2D) the station registration code defining jumpers 195, 196 and 197 will be able to impress 10 the particular code signified by these jumpers resulting in the reenergization of the continuity indicating pulsing relay CBP², this relay CBP², which was picked up and stuck up during the initiating period, having been deenergized upon 15 picking up of the stepping relay 6 as the result of the opening of back contact 172 of this relay 6. This new energizing circuit for the relay CBP² may be traced as follows:—starting at the terminal (+) of the way station battery, station 20 registration code defining jumper 196, front contact 198 of the stepping relay 6, back contact 199 of the stepping relay 7, back contact 200 of the stepping relay 8, wire 201, front contact 202 of the relay LIR², front contact 34 of the slow acting 25 relay SR², through the lower winding of the relay CBP² to the other terminal (—).

Picking up of the relay CBP², with the field battery selecting relay FBS now energized (as heretofore explained) lifting of the contact 177 30 of this relay CBP² will effect opening of the line B, the source of energy now being at the field end of the system, the office battery being disconnected because the office battery selecting relay OBS is energized, and since the relays CAP², 35 PAP² and PBP² (see Fig. 2C) are deenergized, current of negative polarity will flow in the line A, this because the line A at the field end thereof is connected to the positive terminal of the battery, thus resulting in a negative code for the line A and a zero code for the line B during the first station registration period of the indication cycle, as shown in Fig. 3 of the drawings.

Referring now to Figs. 2A and 2B of the drawings, let us observe what effect negative energization of the line relay LA⁰ and deenergization of the line relay LB⁰ will have on the polarity code signifying relays A⁰ and B⁰ and on the continuity code signifying relays M⁰ and N⁰. With the relay LA⁰ energized toward the left, the following circuit will be closed for the relay A⁰ (see Figs. 2A and 2B): beginning at the terminal (—) of the central office battery, contact 180 of the relay LA⁰ toward the left, front contact 181 of the relay SR⁰, wire 205, back contact 206 of the stepping relay h, front contact 207 of the relay f, winding of the relay A⁰, thus resulting in operation of the relay A⁰ toward the left. Since the line A is energized and the line B is deenergized, current of negative polarity will be applied to the continuity code signifying relay N⁰ through the following circuit:—beginning at the terminal (—) of the central office battery, front contact 208 of the relay LAP⁰, back contact 209 of the relay LBP⁰, wire 210, back contact 211 of the stepping relay h, front contact 212 of the stepping relay f, through the winding of the continuity code signifying relay N⁰, to the common return wire C connected to the mid-point of the central office battery, thus operating the relay N⁰ to the left. During the next deenergized condition of the lines A and B, that is during the next stepping period, the code relay KO—1 will be picked up through the following circuit: beginning at the terminal (+) of the central office battery, 70 contact 215 of the relay N⁰, to the left (see Fig.

2B), contact 216 of the relay A⁰ to the left, jumper 217, lower winding of the code relay KO—1, front contact 218 of the stepping relay f, back contact 219 of the stepping relay g, back contact 103 of the half-step relay HS⁰, wire 239, back contact 220 of the relay LBP⁰, back contact 221 of the relay LAP⁰, to the terminal (—). With the code relay KO—1 energized, it is stuck up through its stick contact 222 and the front contact 10 of the relay SR⁰ in series.

The double zero code for causing the stepping relays to take their second step to effect picking up of the stepping relays g and 7 is obtained by the picking up of stepping relay f in the central office applying current of negative polarity to the upper winding of the half-step relay HS⁰, thereby causing the currents in the two windings of the relay HS⁰ to neutralize each other and causing this relay HS⁰ to assume its deenergized position shifting its contact 105 from the raised 15 to the lower position, and thereby resulting in the energization of the lower winding of the impulsing relay IM through a circuit readily traced and including the front contact 109 of the stepping relay f. Energization of the impulsing relay IM will of course break the circuits of both lines 20 A and B and thereby cause the second stepping relays at the central office and at the particular way station now transmitting indications to the central office (and the corresponding stepping relay at the central office to cause their second stepping relay), namely stepping relays g and 7, to be picked up all in a manner similar to that 30 already described hereinbefore in connection with other stepping relays. These relays g and 7 are 35 then stuck up through their stick contacts 223 and 228 respectively.

With the stepping relay 7 (see Fig. 2D) picked up, a particular code as determined by the code jumpers 195 and 197 causes the relays CAP² and 40 PBP² to be picked up through the following respective circuits: (1) beginning at (+), jumper 195, contacts 270, 271, wire 203, contact 272, 45 through the winding of relay CAP², to (—) and (2) beginning at (+), jumper 197, contacts 273 and 242, wire 246, contact 274, through the winding of relay PBP² to the (—) terminal of the battery, (see Fig. 2C). The picking up of relay CAP² effects the opening of line A and the picking up of the relay PBP² causes current of positive 50 polarity to be applied to the field end of the line B, resulting in current of negative polarity flowing in the line B, so that the next code is in effect a zero-minus code as indicated for a second station registration code, as indicated in 55 Fig. 3 of the drawings.

Let us now observe what effect this zero-minus code will have on the apparatus in the central office. With the line A deenergized, the position of the code relay A⁰ will not be changed; but with the line B energized negatively, the line relay LB⁰ assumes its left-hand position. Therefore, current of negative polarity is applied to the code relay B⁰ through the following circuit:—beginning at the terminal (—), contact 224 of the relay LB⁰ to the left, (see Fig. 2A), wire 225, back contact 226 of the stepping relay h, front contact 227 of the stepping relay f, winding of the relay B⁰ to the common return wire C, thus operating 70 relay B⁰ to the left. Also, under this condition of the lines A and B, the relay LAP⁰ will be deenergized and the relay LBP⁰ will be energized, so that the relay N⁰ is energized to the right through the following circuit:—beginning at the terminal (+), front contact 209 of the relay LBP⁰ (see 75

- Fig. 2A), wire 210, back contact 211 of the relay h , front contact 212 of the relay f , winding of the relay N^0 , to the common return wire C , thus energizing the relay N^0 to the right.
- 5 The relay M^0 will be energized to the left through the following circuit: beginning at the terminal (—), back contact 221 of the relay LAP^0 (see Fig. 2A), front contact 220 of the relay LBP^0 , wire 229, back contact 230 of the relay h , front contact 231 of the relay f , winding of the relay M^0 , to C thus operating the relay M^0 to the left. During the next stepping period, namely when the relays LAP^0 and LBP^0 both have assumed their deenergized positions, the following pick-up circuit for the code relay $KO-2$ will be closed:—beginning at the terminal (+), contact 215 of the relay N^0 to the right (see Fig. 2B), contact 233 of the relay M^0 to the left, contact 234 of the relay B^0 to the left, through jumper 235, front contact 20 236 of the relay $KO-1$, winding of the relay $KO-2$, front contact 237 of the stepping relay g , back contact 238 of the stepping relay h , front contact 103 of the half-step relay HS^0 , wire 239, back contact 220 of the relay LBP^0 , back contact 25 221 of the relay LAP^0 , to the other terminal (—) of the central office battery. With this relay $KO-2$ picked up it will be stuck up through a stick circuit including the stick contact 232 and the front contact 46 of the relay SR^0 in series.
- 30 The third zero-zero code, namely both lines de-energized, will be effected by the impulsive relay IM in a manner as already explained, and will result in picking up of the stepping relays h and g , and the indication code will then be transmitted in a manner presently described. With relays h and g once picked up they will be stuck up through their respective stick contacts 240 and 242 until the end of the indication cycle. Although four distinctive conditions can be transmitted at the same time during this third step of the indication cycle, as is obvious from the fact that four front contacts 211, 230, 206 and 226 are available for this purpose, only one of these conditions has been specifically shown in the drawings, namely the condition of occupancy of the detector track circuit containing track relay TR (see Fig. 2D) as manifested by the current flowing in front contact 226 of relay h . It will be noted that with the stepping relay g energized, 40 the polarity indication pulsing relay PBP^2 will be energized through the following circuit, whereas the relay CAP^2 , CBP^2 and PAP^2 will remain de-energized:—beginning at the terminal (+) of the way station battery, back contact 241 of the 45 track relay TR , front contact 242 of the stepping relay g , wire 246, front contact 274 of the relay LIR^2 , winding of the relay PBP^2 . With the relay PBP^2 energized and relays CAP^2 and CBP^2 and PAP^2 all deenergized, the (+) terminal of the 50 end battery will be connected to both the line A and the line B through front contacts 248 of the relay FBS , and through front contact 250 of relay PBP^2 , back contact 251 of relay PAP^2 , back contact 252 of relay CAP^2 and back contact 177 of 55 relay CBP^2 , thus resulting in negative current flowing in the lines A and B and resulting in a minus-minus code for an indication code in the indication cycle (see Fig. 3).
- 60 Let us now observe what effect this minus-minus code will have on the central office apparatus. Relays LA^0 and LB^0 are actuated toward the left and relays LAP^0 and LBP^0 are picked up as a result of the minus-minus code. With the relay LB^0 actuated to the left the following circuit for the indication relay IR is 65 closed:—beginning at the terminal (—) of the central office battery, contact 224 of the relay LB^0 to the left, wire 225, front contact 226 of the stepping relay h , front contact 243 of the relay $KO-2$, wire 244, winding of the relay IR , to C . The completion of this circuit results in the operation of the polar-magnetic stick relay IR to the left thereby illuminating the indicating lamp I through the contact 245.
- 70 The picking up of the last stepping relay h in the central office will result in the deenergization of the half-step relay HS^0 , and dropping of this relay HS^0 and the shifting of the contact 105 of relay HS^0 results in energization of the impulsive relay IM , which upon lifting of its contacts 38 and 39 opens the lines A and B to effect further stepping of the system. Since, however, there are no more stepping relays to function, the impulsive relay IM will not be deenergized as it was heretofore through the medium of the next 75 stepping relay picking up, and therefore this impulsive relay IM will remain energized, maintaining the break in the lines A and B , which after a short interval of time results in deenergization of the slow acting relays SR^0 and SRP in the central office, and dropping of the slow acting relay SR^2 at the particular way station under consideration, which in turn results in dropping of the various relays OBS , SE^0 , FST , f , g and h , in the central office, and resulting in dropping of the relays LIR^2 , SE^2 , OT , FBS , 6, 7 and 8 in the way station under consideration, so that upon deenergization of these various relays the lines A and B are returned to their normal condition, 80 under which condition line A is deenergized and line B is energized by current of positive polarity.
- 85 Referring back to the control cycle operation, attention is directed to the fact that although only one distinctive control impulse was transmitted during the control cycle described, this 90 control impulse passing through the front contact 68 of the stepping relay 3 and resulting in the operation of the switch machine relay SMR , that four distinctive control impulses can be transmitted on the same step, namely the third step of 95 a control cycle. Similarly even though only a single indication has been described as being transmitted in the indication cycle, this indication impulse passing through the front contact 226 of the stepping relay h (see Fig. 2B) and resulting in the operation of the indicating relay IR , it is to be understood that four distinctive indications can be transmitted on this same step, 100 namely, the third step of the indication cycle. Also, even though only one way station has been 105 illustrated in Figs. 2C and 2D of the drawings, it is of course understood that the system as disclosed is capable of communicating with sixty-four different way stations, this being apparent from the fact that eight relays corresponding to 110 the code relay $SO-1$ may be employed, and for each of these relays $SO-1$ eight code relays $SO-2$ may be used, so that the entire system 115 may have sixty-four relays corresponding to the code relay $SO-2$.
- 120 It should also be noted that the station selecting and pulsing determining relay LIR^2 can pick up only at one way station at one time, this being accomplished by a so-called geographic lock-out which is accomplished by the contact 177 of the relay CBP^2 (see Fig. 2C), this because the first relay CBP^2 only of any number of similar relays that may be up during the initiation period of an indication cycle will complete a circuit for its associated relay LIR^2 , this because 125

the line B beyond the first station that has its relay CBP^2 up will be open, so that the remaining LIR relays will not be picked up. It is of course readily apparent that the indication-only selecting relays, such as the relays SE^0 and SE^2 , are used for the purpose of starting the cycle at the fourth stepping relay in the particular arrangement of the relays illustrated and that these relays SE^0 and SE^2 are only up during an indication cycle and are not up during a tandem cycle during which indications are transmitted in addition to the transmission of control impulses.

Attention is directed to the fact that the circuits for the relays M^0 , N^0 , M^2 and N^2 are open at the line repeater relays LAP^0 , LBP^0 , LAP^2 or LBP^2 during each zero-zero code, this in order to prevent the circuit for these relays operating such relays during such stepping impulse and during which the code relays, such as $SO-1$ and $KO-1$ are operated in accordance with the positions of the relays A^0 , B^0 , M^0 , N^0 , A^2 , B^2 , M^2 and N^2 .

Tandem cycle.—Let us now assume that the operator moves a lever, such as the lever L^1 , say from its dotted position back to its solid line position to operate the switch machine SM back to its normal position, and that the office starting relay OST is picked up in a manner as already explained in connection with the control cycle (see Fig. 3), and that the line B is opened at the contact 177 (see Fig. 2C), because the relay CBP^2 has been picked up in response to dropping of the change relay CH , by reason of the fact that an indication is to be transmitted from the way station, shown in Fig. 2C, to the central office, this because the relay TR has been picked up and has momentarily broken the stick circuit of this relay CH at contact 160 . Under this condition the relay LIR^2 will be picked up through the front contact 177 of relay CBP^2 and the front contact 176 of the relay LAP^2 , so that the station nearest the control office is rendered effective to transmit indications. Since the line A is energized negatively during the conditioning period, the SE relays in the control office and at the field stations are not energized, and the stepping starts with the group of relays for the transmission of controls, the same as if the cycle was to be a control cycle alone. The opening of the line B, prior to the initiation of the cycle, however, results in the energization of the relay OT at the end of the line, which is the case with an indication cycle alone.

In the same manner as already explained, the slow acting relays SR^0 and SRP (see Fig. 2A of the drawings) and the slow acting relay SR^2 (see Fig. 2C of the drawings) are picked up, as a result of which the relay LIR^2 (see Fig. 2C) will be stuck up, and the impulsing relay IM (see Fig. 2B) will be energized, thereby opening its contacts 38 and 39 opening both the line A and the line B, and resulting in a zero-zero code comprising the first stepping character as indicated in the table headed "tandem cycle" in Fig. 3 of the drawings. This breaking of the lines A and B will cause the stepping relays a and l to be picked up in a manner as already explained. Since the station to be selected is the same as the station selected during the description of the control cycle, the next four steps of the tandem cycle will be exactly the same as that of the control cycle, as clearly indicated in the column "tandem cycle" shown in Fig. 3 of the drawings. The control code character itself, however, will be slightly different, in that under this condition

the line A will be energized by current of positive polarity, whereas for the transmission of the control code as indicated in the "control cycle" column of Fig. 3 was of minus polarity. In other words, the switch machine relay SMR is operated back to its right-hand position by reason of the fact that the lever L^1 has been returned to its normal plus polarity position.

At the end of the control cycle, as previously explained, the relay OBS in the control office picks up and connects the lines A and B together to the common wire, and the impulsing relay IM drops to close the lines A and B in the control office. This de-energization of the lines A and B picks up the relay FBS (see Fig. 2D) in multiple with the stepping relay 6 , the relay OT being energized in the case assumed; and when the relay FBS is thus picked up, the battery 11 at the field station is coupled to the lines A and B, so that the system continues stepping for the transmission of indications.

Thus, the so-called tandem cycle in effect consists of an indication cycle immediately following a control cycle, without an intervening period of blank with the system in the normal condition. The purpose of this arrangement is to avoid holding back the transmission of indications while controls are being transmitted from the control office. In the system of the type described, in which the line circuits are employed at one time for transmitting controls out, and at another time for transmitting indications into the control office, it is evident that controls and indications cannot be transmitted simultaneously; and instead of transmitting controls alone on repeated cycles so long as there are any new controls to be transmitted, holding back transmission of indications, during such time, in accordance with this invention, the so-called tandem cycle is provided with the result that controls and indications are transmitted alternately so long as both are ready, neither the indications being unduly delayed for the controls or vice versa. By reason of this organization, the operator may use the line freely, knowing that in so doing no indications are being suppressed.

Obviously, since the indication to be transmitted from the way station to the central office during this tandem cycle originated at the same way station as did the indication transmitted during the indication cycle, the station registration code transmitted during the fifth and sixth step, namely, when relays f and g and 6 and 7 are picked up will be exactly the same as the codes transmitted during the indication cycle, so that the next four code steps of the tandem cycle will be the same and will be carried out in exactly the same manner as already described in connection with the indication cycle. The last code step or "indication code" will, however, be different in that picking up of the track relay TR will leave the circuit heretofore traced and including the contact 241 of this track relay TR open, so that the relay PBP^2 will not be energized during the indication code period, and the line A will be connected to the positive terminal of the end battery and the line B will be connected to the negative terminal of the end battery, so that current of negative character will flow in the line A but current of positive polarity will flow in the line B. This indication code of minus-plus will result in plus polarity being applied to the indication relay IR (see Fig. 2A) because the contact 224 of relay LB^0 will assume its right-hand position during this indication code step and will oper-

ate the relay IR to its right-hand normal position by current in a circuit heretofore traced, extinguishing the lamp I.

In order to avoid undue complication of the drawings and unnecessary elaboration in the description the present invention has been illustrated to show only a single way station in Figs. 2C and 2D, although two way stations have been illustrated in Fig. 1 of the drawings, and in this connection it is to be understood that the invention may be extended to employ 64 way stations without additional apparatus than what has been illustrated except that a station selecting relay, such as the relay SO-2, and a station registration relay such as the relay KO-2 are necessary for each way station, and additional relays corresponding to the station selecting relay SO-1 and the station registration relay KO-1 are necessary for each eighth way station. Also, in this connection attention is directed to the fact that only one of the station selecting and pulsing determining relays LIR², even though sixty-four relays of this kind may be used, can be energized at one time, so that in-coming codes can be pulsed or initiated at only one way station at one time, and obviously this coding or impulsion of the lines cannot interfere with the coding or impulsion at the central office by reason of the interlock between the field starting relay FST and the office starting relay OST shown in Fig. 2A of the drawings, also, since the office battery selecting relay OBS and the field battery selecting relay FBS are either both energized or both deenergized is another reason for avoiding an in-coming and an out-going code being transmitted at the same time.

The relay OT known as an indication conditioning relay is a relay that determines that the field battery selecting relay FBS shall be picked up as soon as the stepping relay f and its corresponding stepping relay 6 is picked up. In other words, the relay OT determines that an indication is to be transmitted from a way station to the central office and this relay OT through the medium of its front contact 260 will pick up the field battery selecting relay FBS simultaneously with the picking up of the stepping relay 6, this through the medium of the wire 261 included in the pick-up circuit for the field battery selecting relay FBS. The battery selecting relay FBS will of course be stuck up through its stick contact 262 as soon as it has once been energized, and in a similar manner the relay OT will be stuck up through its stick contact 263 when it has once been picked up, the stick circuits for these relays OT and FBS include the contact 35 of the slow acting relay SR², so that both of the relays OT and FBS will again be deenergized during the period of blank, known as the normal period in the three different cycles illustrated in Fig. 3 of the drawings. It may be pointed out here that the resistance units 265¹ and 265² shown in Fig. 1 of the drawings (the unit 265² also being shown in Fig. 2C of the drawings), are of such ohmic value that the current flow through the pick-up winding of the relay LIR² will be the same for each of these relays irrespective of the distance the way station under consideration is located from the central office. In other words, these resistance units 265¹ and 265² may be said to be current balancing resistance units.

From the foregoing description, the general operating characteristics of each of the relays employed in the system under consideration should be understood, but in order to more clearly

understand the conventions employed, these conventions will be further discussed. It will be noted that the relays A⁰, B⁰, M⁰, N⁰ and IR, located in the central office, and the relays A², B², M², N² and SMR located in the first way station of the system, each have a small black square near the lower righthand corner thereof. This conventional illustration represents these relays as being stay-where-put relays, that is, these relays will remain in their last energized position, and are polar relays. They may also be called polar two-position relays, or permanent magnet stick relays. The relays SR⁰, SRP and SR² are slow acting relays as indicated by the shaded portion at the lower end of the coil, signifying a short circuiting coil or slug, and these relays are in fact slower in dropping than they are in picking up, so that they may be said to be slow dropping relays. The relays CSA, CSB, LA⁰, LB⁰, LA² and LB² are all polar relays of the non-stick three-position type, which are biased to their neutral position. The remaining relays illustrated are relays of the neutral type, which in some cases are stick relays and in other cases do not include a stick circuit. The operating characteristics of these various relays may be somewhat different in order to carry out the desired operation of the system as heretofore described.

Attention is again directed to the code jumpers 50, 51 and 52 shown in Fig. 2A of the drawings, and the code jumpers 195, 196 and 197 shown in Fig. 2D of the drawings, these jumpers define the particular codes used for selecting the way station in Figs. 2C and 2D, and in registering this same way station at the central office, respectively. Obviously, these code jumpers may vary in number and may be applied in various ways to obtain the 64 distinctive combinations necessary to select any one of 64 different way stations or register such way stations. In this connection it should be noted that four instead of three (jumpers 50, 51 and 52) could have been used in the central office, and it is because the fourth jumper was omitted that a zero appeared in the second station selecting period of the control cycle (see Fig. 3). For the same reason, a zero appeared in the second station registering step of the indication cycle (see Fig. 3) because no jumper was present in either the fifth or sixth jumper location of Fig. 2D, only three jumpers 195, 196 and 197 having been employed. Also, the code jumpers 217 and 235 shown in Fig. 2B, and the code jumpers 89 and 139 shown in Fig. 2D of the drawings, illustrate how a particular way station may be selected or may be registered at the central office, providing that the code transmitted is in conformity with the code defined by the manner in which these code jumpers are connected. As already heretofore pointed out, there would be in the central office if the system were extended to take care of 64 way stations, 8 relays corresponding to the relay KO-1, and there would be eight relays corresponding to the relay KO-2 for each of the relays KO-1, so that there would be a total of 64 relays corresponding to the relay KO-2.

Referring to Figs. 2C and 2D of the drawings, it will be noted that certain of the wires are shown by heavy lines. These heavy wires are only used at the last way station, and comprise part of the apparatus necessary to control the relays in the "end battery control station" (see Fig. 2D). The net result is that an intermediate station is exactly the same as the last station except for the 75

omission of the heavy wires and the different disposition of the code jumpers.

Having thus shown and described one specific embodiment of the present invention, it is desired to be understood that the particular embodiment illustrated is only a single exemplification of applicant's invention and is not intended to illustrate the particular circuit arrangement necessarily used in carrying out the present invention, but has been selected for the purpose of disclosing the underlying principles of the invention and its mode of operation rather than its scope or the exact construction preferably employed in practicing the same, and it is further desired to be understood that the circuits may be varied in many respects in order to meet the problems encountered in practicing the invention or to embody the particular type of relays to be employed, that the system may be varied in the number of way stations to which the invention is applied in a single system, and the amount of apparatus to be installed at a particular way station, all without departing from the spirit or scope of the invention or the idea of means underlying the same, except as demanded by the scope of the following claims.

What I claim as new is:

1. In a selector system comprising a line circuit including a plurality of polar line relays in series one at a central office and one at each of a plurality of field stations, a series of stepping relays at said central office and at each of said field stations divided into two separate portions, means for operating one portion for transmitting distinctive code impulses from the central office to a particular field station, means for operating the other portion for transmitting distinctive indications from any field station to said central office, means for selectively determining whether one or both of said portions are to be operated and for effecting successive picking up of said stepping relays of the portions selected, means for transmitting code impulses from said central office during successive energization of the stepping relays of one of said portions and for transmitting code impulses from a particular way station during successive energizations of the stepping relays of said other portion whereby there cannot be a conflict between in-coming and out-going codes for the several field stations, and means including said polar line relays for receiving said code impulses.

2. Code storing means for storing the code transmitted over two circuits comprising, a first pair of polar two-position stay-where-put relays, means for operating each of said first pair of relays in accordance with the polarity of current flowing in its respective one of said two circuits, a second pair of polar two-position stay-where-put relays, means for operating each of said second pair of relays to one position when its corresponding one of said two circuits is energized and to the opposite position when its corresponding one of said two circuits is deenergized, means for deenergizing all of said two-position relays when both of said circuits are deenergized, and code defining circuits including contacts of said two-position relays.

3. Code storing means for storing the code transmitted over two circuits comprising, a first pair of polar two-position stay-where-put relays, means for operating each of said first pair of relays in accordance with the polarity of current flowing in its respective one of said two circuits, a second pair of polar two-position stay-where-

put relays, means for operating each of said second pair of relays to one position when its corresponding one of said two circuits is energized and to the opposite position when its corresponding one of said two circuits is deenergized, means for de-energizing all of said two-position relays when both of said circuits are deenergized, and means including said relays for storing said code.

4. A selector system comprising, two line circuits connecting a central office and a plurality of field stations, a series of stepping relays at said central office and at each of said field stations, means for energizing and de-energizing said circuits, means for causing the next succeeding stepping relay in each of said series to pick up in response to simultaneous deenergization of both of said circuits, code character creating means at said central office for energizing said circuits by current of one or the other polarity or deenergizing one of said circuits, and means at each field station for deciphering such code character during a particular step of said stepping relays, whereby any one of eight distinctive code characters results so that codes build up at the rate of eight having an exponent equal to the number of stepping relays.

5. In a remote control system; a control office, a plurality of field stations; a normally-at-rest selector type communication system interconnecting said control office and said field stations and capable, when initiated, of operating through cycles of operation for the transmission during each cycle of control codes and/or indication codes, said transmission of control codes and indication codes occurring during separate portions of a particular cycle; and means at said control office and at each of said field stations for initiating said communication system, whereby control codes alone are transmitted on a cycle when said initiating means at said control office is actuated, whereby indication codes alone are transmitted on a cycle when an initiating means at a field station is actuated, and whereby control and indication codes are transmitted on the same cycle when said initiating means at said control office and said initiating means at a field station are actuated substantially simultaneously.

6. In a selector system comprising a line circuit including a plurality of polar line relays in series one at a central office and one at each of a plurality of field stations, a series of stepping relays at said central office and at each of said field stations, each series of which is divided into two separate portions one portion of which is used for the transmission of distinctive code impulses from the central office to a particular field station and the other portion of which is used for the transmission of distinctive indications from any field station to said central office, selectively controlled means for effecting the successive picking up of said stepping relays of either or both portions of said stepping relays, and means for transmitting code impulses from said central office during successive energization of the stepping relays of one of said portions and for transmitting code impulses from a particular way station during successive energizations of the stepping relays of said other portion, whereby there cannot be a conflict between in-coming and out-going codes for the several field stations.

7. In combination, a control office, a plurality of field stations, line circuit means connecting said control office with said field stations, code transmitting means at said control office and at each of said field stations for at times impressing

- a series of coded impulses on said line circuit means, means for allowing only one of said code transmitting means to operate at any one time when several code transmitting means are ready 5 to operate, and means causing said control office code transmitting means to operate at alternate times with said field station code transmitting means when several field station code transmitting means are ready to operate at the same 10 time that said control office code transmitting means is ready.
8. In a selective code system, two line circuits having a plurality of code combinations applied thereto, means applying said code combinations by energizing either or both of said line circuits with current impulses of positive or negative polarities and deenergizing both said line circuits between such code combinations, step-by-step means caused to take one step for each deenergized period of both line circuits between successive code combinations, a relay for storing the particular polarity of one of said line circuits for each of said code combinations until there is a change of polarity for a succeeding code combination, another relay for storing the particular polarity of the other of said line circuits for each of said code combinations until a change of polarity for a succeeding code combination, relay means for storing whether one or the other or both of said line circuits is energized for each of said code combinations until there is a change in condition of said line circuit for a succeeding code combination, and means selectively controlled on each of a plurality of steps of said step-by-step 30 means in accordance with the composite condition of said relay, said another relay and said relay means for the code combination preceding that step.
9. In a selective code system, two line circuits, means applying a code combination to said line circuits by energizing either or both of said line circuits with current of positive or negative polarity, whereby any one of eight different code combinations is applied, one polar relay controlled in accordance with the polarity of the current in one of said line circuits, another polar relay controlled in accordance with the polarity of current in the other of said line circuits, relay means controlled in accordance with whether one 40 or the other or both of said line circuits are energized irrespective of polarity, circuit means controlled by said one and said another polar relays when said relay means is controlled in accordance with the energization of both of said line circuits, circuit means controlled by said one polar relay only when said relay means is controlled in accordance with only the energization of said one line circuit, and circuit means controlled by said another polar relay only when 45 said relay means is controlled in accordance with only the energization of said other line circuit.
10. In a selective code system, two line circuits having a plurality of code combinations applied thereto, means applying said code combinations to said line circuits by energizing either or both of said line circuits with current impulses of positive or negative polarities and deenergizing both said line circuits between such code combinations, whereby any one of eight different code 55 combinations is applied between successive deenergized periods of both said line circuits, step-by-step means caused to take one step for each deenergized period between successive code combinations, a first code means selectively responsive 60 on the first step to the code combination, a sec-

ond code means selectively responsive on the second step to the second code combination depending upon whether said first code means is selected, and other means controlled by said code combinations on succeeding steps dependent upon 5 whether said second code means is selected.

11. In a remote control system, a control office, a plurality of field stations, a first line and a plurality of other lines connecting said control office with said field stations, means for applying 10 a series of distinctive impulses to said first line, means for selectively completing the first line circuit through one or more of said other lines to form different combinations, a first means included in series in said first line at each of said 15 field stations selectively responsive to the character of said impulses, a second means included in series in one of said other lines at each of said field stations responsive to said impulses, and means at each field station controlled by said 20 first means and said second means in combination for selecting one of said field stations in accordance with composite characteristics of said series of impulses and the selected combinations of other lines for each of said impulses of the 25 series.

12. In a remote control system, a control office, a plurality of field stations, a first line and a plurality of other lines connecting said control office with said field stations, step-by-step mechanisms at said control office and at said field stations, means at said control office for applying a series of distinctive impulses to said first line, means selectively completing the first line circuit through one or more of said other lines to form 30 different combinations of line circuits, means at said control office and at each field station responsive to said series of impulses for operating said step-by-step means in synchronism, a first means included in said first line at each of said 35 field stations for selectively responding to the character of said impulses, a second means associated with said other lines at each of said field stations for responding to the different combinations of line circuits, and means controlled 40 by said first and said second means in combination for selecting one of said field stations.

13. In a remote control system, a control office, a plurality of field stations, a line circuit connecting said control office with said field stations, 50 means for storing the condition that a plurality of outbound and inbound code messages each comprising series of distinctive impulses simultaneously await transmission, means for transmitting first one of said outbound messages over said line 55 circuit to said field stations, and means for thereafter alternately transmitting the remaining stored inbound and outbound messages over said line circuit.

14. In a remote control system of the selector 60 type, the combination with a control office and a plurality of field stations, of a first line and a plurality of other lines connecting said office with said stations, means for energizing said first line with a plurality of distinctive impulses 65 separated by time spaces, selective mechanism at said office and at said stations operated in synchronism during said time spaces, means controlled by said mechanisms at said office or at said stations for selectively connecting said other 70 lines to said first line whereby said other lines are distinctly conditioned, means controlled by the character of said impulses and said distinctive conditioning of said other lines at said office for selecting one of said stations, and means con- 75

trolled by the character of said impulses and the distinctive conditioning of said other lines at said stations for registering one of said stations in said office.

5 15. In a remote control system of the selector type, the combination with a control office and a plurality of field stations, a first line and a plurality of other lines connecting said office with said stations, means for energizing said first line with a plurality of impulses separated by time spaces, selective mechanism at said office and at said stations operated in synchronism during said time spaces, means controlled by said mechanism for selectively connecting said other lines to said first line whereby said other lines are distinctively conditioned, and means for transmitting distinctive messages over said first line and said other lines from the control office to any one field station or from any one field station to the control office, each distinctive message including a combination of positive current, negative current or zero current on one of said other lines.

25 16. In a selector system of the distinctive code type; a central office and a plurality of field stations connected by a line circuit; code creating and code deciphering means at said office and at each of said stations, the code creating means at said office including step timing apparatus; means including said code creating and said code deciphering means for alternately transmitting and receiving respectively codes over said line circuit from said office to any of said stations and from any of said stations to said office when there are a plurality of codes ready for transmission, each code comprising a plurality of distinctive elements; and means controlled over said line circuit by the code creating means in said office for causing said step timing apparatus 40 to determine the rate of stepping of said apparatus.

45 17. In a selector system of the distinctive code type; a central office and a plurality of field stations connected by a line circuit; code creating and code deciphering means at said office and at each of said stations, said code creating means including stepping apparatus at said office which opens said line circuit when a step is to be taken; means including said code creating and said code deciphering means for transmitting codes over said line circuit from said office to any of said stations and from any of said stations to said office, each code comprising a plurality of distinctive impulses impressed on said line circuit, only one of said code creating means being operable at a time; and means controlled over said line circuit by the code creating means in said office for determining the rate of stepping of said apparatus.

50 60 18. In a remote control system, a first line circuit and a second line circuit each having a plurality of series of time spaced impulses of selected characters impressed thereon, a step-by-step mechanism operable through a separate cycle for each of said series of impulses, means controlled by said mechanism for selecting four local channel circuits for each step, means for causing said mechanism to take one step for each time space between successive impulses of a series, means for distinctively energizing two of said channel circuits each in accordance with the character of the impulse on its respective one of said line circuits for that step, and means for distinctively energizing the other two of said channel circuits 70 each in accordance with the energized or de-en-

ergized condition of its respective one of said line circuits for that step.

75 19. In a remote control system, a first line circuit and a second line circuit each having a plurality of series of time spaced impulses of selected characters impressed thereon, a step-by-step mechanism operable through a separate cycle for each of said series of impulses, means controlled by said mechanism for selecting four local channel circuits for each step, means for causing said mechanism to take one step for each time space between successive impulses of a series, means for distinctively energizing two of said channel circuits each in accordance with the character of the impulse on its respective line 15 circuit for that step, means for distinctively energizing the other two of said channel circuits each in accordance with the energized or de-energized condition of its respective one of said line circuits for that step, and electro-responsive 20 means for each of said channel circuits, each being responsive to said distinctive energization of its respective channel circuit, whereby said electro-responsive devices for each step are positioned in any one of eight distinctive combinations.

25 20. In a remote control system, a control office, a plurality of field stations, a plurality of line circuits connecting said office with said stations, a source of energy at the end station of said plurality of stations, means in said office for closing and opening said line circuits to impress time spaced impulses thereon, the energy for such impulses being derived from said source, transmitting means at each station for closing, opening and transposing said line circuits in advance of the impression thereon of said impulses whereby said line circuits are distinctively conditioned in various combinations for each of said impulses, and means for preventing more than one of said 40 stations conditioning any of said line circuits at any one time.

30 35 45 50 55 60 65 21. In a selector system, two line wires and one common return wire extending from a control office through a plurality of field stations, a polar line relay at each of said field stations and at said control office included in each of said line wires, a source of current at each end of the system, means for transmitting codes from said control office to said field stations over said line wires and said common return wire by impulses of selected polarity derived from the source of current located at one end, means for transmitting similar codes from any one of said field stations to said control office over said line wires and said common return wire by similar impulses derived from the source of current located at the other end, means at the transmitting field station for selectively determining the polarity of said similar impulses, means at said control office and at one of said stations for selecting one or the other of said sources of current in accordance with the direction of transmission over said line wires, and means including said polar line relays for selectively receiving said codes.

70 75 80 85 90 95 22. In a selector system; two line wires and one common return wire extending from a control office through a plurality of field stations; a polar line relay at each of said field stations and at said office included in each of said line wires; means for transmitting eight distinctive codes in each direction over said line wires and said common return wire; means including said polar line relays for selectively receiving said codes; means responsive to the codes transmitted outward from

said office for selecting individual field stations and for transmitting individual control codes to selected stations only; means responsive to the codes transmitted inward to said office for identifying individual field stations and for transmitting individual indication codes from identified stations only; means including said polar line relays for selectively receiving said codes, each code comprising a combination of current applied to 10 said two line wires of plus-plus, plus-minus, plus-zero, minus-plus, minus-minus, minus-zero, zero-plus, and zero-minus.

23. In a remote control system; a control office; a plurality of field stations; a normally at 15 rest selector type communication system interconnecting said control office and said field stations and capable when initiated into a cycle of operation of transmitting out-bound control codes and in-bound indication codes, said system 20 operating to transmit only in one direction at the same time and operating to transmit from only one field station at the same time; means at said control office for initiating said communication system into a cycle of operation for transmitting 25 a control code only; means at each of said field stations for initiating said communication system into a cycle of operation for transmitting an indication code only; and means causing control and indication codes to be alternately transmitted 30 during the same operating cycle when said initiating means at said control office and an initiating means at one of said field stations are actuated substantially at the same time.

24. A remote control system for transmitting 35 indications from a field station to a control office over two line circuits, step-by-step means in the control office and at the field station operated synchronously to take a step upon de-energization of both of said line circuits, means at the 40 control office governed by its step-by-step means for intermittently opening and closing said line circuits, a source of current at the field station for energizing said line circuits, means at the field station governed by its step-by-step means 45 to distinctively vary the energized conditions of said line circuits, said means rendered effective after each de-energization of both of said line circuits to determine the next succeeding energized condition of said line circuits in accordance with 50 the indications to be transmitted, and indicating means in the control office responsive distinctively to the variations in the energized conditions of said line circuits for each step.

25. A remote control system of the character 55 described for transmitting indications from any one of a plurality of field stations to a control office over a line circuit comprising, means for intermittently energizing said line circuit, step-by-step means in the control office and at each 60 field station operated synchronously to take one step in response to each de-energization of said line circuit, a battery at the most distant field station, pole-changing means in said line circuit at each field station, circuits controlled by said 65 stepping relays at the field station for controlling said pole-changing means at that station successively during each de-energization of said line circuit in accordance with the indications to be transmitted, and indicating means in the control 70 office governed by its stepping relays for responding to the polarity of energization of said line circuit for each step.

26. In a remote control system for transmitting 75 controls from a central office to a field station for governing the operation of devices and for

transmitting indications from said field station to the control office of the operated condition of said devices comprising, line wires connecting the control office and the field station, a series of stepping relays at the control office and at the field station arranged in two groups for the transmission of controls and indications respectively, means responsive to the energization or de-energization of said line wires for synchronously and sequentially operating said stepping relays one 10 at a time, means in the control office and at the field station for controlling the operating circuits of said stepping relays to cause at times 15 operation of the indication group of stepping relays immediately following operation of the control group, and means at the field station responsive to a change in the condition of said devices calling for the transmission of new indications for governing the operation of said conditioning means to determine if the group of indication stepping relays shall be operated.

27. A remote control system for transmitting controls from a control office to a field station for governing the operation of devices at said station and for transmitting indications of the 20 operated condition of said devices from the field station to the control office comprising, a line circuit connecting the control office and the field station, stepping relays at the control office and at the field station arranged in a control group 25 and an indication group, impulsing means in the control office governed by said group of stepping relays for intermittently opening and closing said line circuit, control starting means in the control office manually operable to condition the system 30 for operation when new controls are to be transmitted, indication starting means at the field station responsive to a change in the condition of said devices calling for the transmission of new indications, and means in the control 35 office and at the field station governed over said line circuit by said control start means and said indication start means for determining which one or both of said groups of stepping relays shall be operated during operation of said impulsing 40 means.

28. In a remote control system, a pair of spaced locations, a plurality of line circuits interconnecting said locations, means at one of said locations for closing and opening said line circuits for 45 impressing thereon time-spaced impulses of current derived from a source of current at either of said locations, transmitting means at both of said locations, means controlled by the transmitting means at both locations for selectively 50 closing and opening said line circuits in various combinations in advance of the impression thereon of said impulses whereby the impulses of current energize said line circuits in various combinations, and means for selecting the particular 55 one of said transmitting means and its respective source of current to be used for impressing said line circuits at any one time.

29. In combination; a line circuit having a series of time-spaced current impulses of different 60 polarity characteristics impressed thereon; a polar line relay for repeating each of said impulses in accordance with its polarity; a neutral relay controlled by said polar line relay for repeating each of said impulses irrespective of its 65 polarity; a series of stepping relays; circuit means controlled by said neutral relay for causing said stepping relays to be picked up sequentially, one for each time space in said series of impulses as 70 repeated by said neutral relay; electro-respon- 75

5 sive means for each step; and circuit means including a front contact of the last stepping relay picked up, and controlled by said polar line relay, for energizing said electro-responsive means for that step in accordance with the polarity of the impulse in said series immediately following the picking up of that stepping relay.

10 30. In combination; a line circuit having a series of time-spaced current impulses of different polarity characteristics impressed thereon; a polar line relay for repeating each of said impulses in accordance with its polarity; a neutral relay controlled by said polar line relay for repeating each of said impulses irrespective of its polarity; a slow-acting relay controlled by said polar line relay so as to be picked up at the beginning of each series of impulses and dropped at the end of such series; a series of stepping relays; circuit means controlled by said neutral relay for causing said stepping relays to be picked up sequentially, one for each time space in said series of impulses as repeated by said neutral relay; other circuit means including a front contact of said slow-acting relay for causing said stepping relays to be maintained picked up until the end of such series of impulses; electro-responsive means for each step; and circuit means including a front contact of the last stepping relay picked up and a contact of said polar relay, for energizing said electro-responsive means for that step in accordance with the polarity of the impulse in said series immediately following the picking up of that stepping relay.

15 31. A remote control system of the character described for transmitting indications from any one of a plurality of field stations to a control office over a line circuit comprising, means at said control office for intermittently closing and opening said line circuit, a series of stepping relays at the control office and at each field station picked up one at a time in response to each de-energization of said line circuit, a battery at the most distant field station, pole-changing means in said line circuit at each field station, circuit means at each field station rendered effective through front contacts of said stepping relays at the field station for controlling said pole-changing means at that station successively during each de-energization of said line circuit in accordance with the indications to be transmitted upon the following energization of said line circuit, and indicating means in the control office controlled through front contacts 20 of its stepping relays for registering the polarity of energization of said line circuit for each step.

25 32. In a selector system of the distinctive code type, a central office and a plurality of spaced field stations, a line circuit connecting said central office and said field stations, code creating means at said office and at each of said field stations operable only one at a time, each of said code creating means impressing different series of polar impulses on said line circuit, whereby 30 codes are transmitted from said office to any of said field stations or from any of said stations to said office each code comprising a plurality of distinctive polar impulses impressed on said line circuit at different times, said code creating means at said central office including timing means located only at said central office for closing and opening said line circuit when an impulse is transmitted, whereby the rate of impulsive 35 pulsing is wholly determined by the same apparatus irrespective of which code creating means

is in operation, step-by-step means at said central office and at each of said field stations operated in synchronism by said impulses, code deciphering means at said central office and at each of said field stations, and means including contacts of said step-by-step means for controlling said code deciphering means by said polar impulses on said line circuit. 5

33. In a remote control system; a control office; a plurality of field stations; a source of current at said control office and another source of current at the last of said field stations; a plurality of line wires extending from said control office through the several field stations; means normally effective while the system is at rest to energize said line wires from said source of current in said control office; initiating means at each of said field stations for at times initiating said system by causing deenergization of said line wires while the system is at rest; control means responsive to the deenergization of said line wires for effecting energization of said line wires from said source of current at said last station; indication transmitting means at each of said field stations for acting on said line wires 20 to transmit a series of code impulses of current derived from said source at said last station over said line wires when said system is initiated by that station; code impulse receiving means at said control office; and lock-out means allowing only one of said field station indication transmitting means to transmit code impulses following any given initiation of the system, thereby requiring the system to be returned to a normal-at-rest condition following a series of code impulses from a field station. 35

34. In a remote control system; a control office; a plurality of field stations; a source of current at said control office and another source of current at the last of said field stations; line 40 wires extending from said control office through the several field stations and arranged to form two line circuits at times including said control office source of current and at other times including said another source of current at said last field station; control transmitting means at said control office for transmitting codes over said line wires to any particular one of said field stations by acting on both said line circuits to impress a series of impulses of current derived 45 from said source of current in said control office; indication transmitting means at each field station for transmitting codes over said line wires to said control office by acting on both said line circuits to impress a series of impulses of current derived from said source of current at said last field station over said line wires; means acting selectively at the beginning of a series of impulses to render either said control transmitting means and said source of current at said control office effective or one of said indication transmitting means and said source of current at the last field station effective; and means for allowing only one of said indication transmitters to be effective during any one series of impulses. 50

35. In a remote control system, three lines, means including a source of current for impressing current of different characteristics simultaneously on each line and means for selecting the impressed current characteristics in accordance with a code involving successive impulses and a combination of current characteristics on each line in each impulse. 55

36. In a remote control system, a plurality of stations, three conductors interconnecting said 60

- stations, a transmitter at a first station sending a call of successive current impulses on combinations of said three conductors, including combinations when no current is sent on certain conductors of each combination, the first impulse of the call being one of several reserved for first impulses of calls, and a receiver at one of the other stations, responsive to the call transmitted from said first station.
- 10 37. A remote control system comprising stations connected by three conductors and signalling devices including a source of current in the stations adapted to communicate one with another in a code characterized by a sequence of impulses and by the presence or absence and polarity of current in certain conductors during each impulse.
- 20 38. In a remote control system, a control station and substations, operating units at said substations, means including three line conductors for communicating messages between the control station and a substation in a code composed of successive impulses on characteristic combinations of said conductors, said message may include a substation call of multiple impulses to identify a desired substation and a signal in a subsequent impulse or impulses to indicate the condition of an operating unit at the called substation.
- 30 39. In a train dispatching system comprising a control station and substations connected by three line wires, a source of current, transmitters at the substations for variably applying current from said source to said line wires, a receiver at the control station adapted to give three indications of conditions at the substation selectively according as the current in a first line wire is positive, negative or zero, and a second receiver at the control station responsive jointly to current in the first line wire and in a second line wire to give additional indications.
- 40 40. In a train dispatching system, stations connected by three line wires, a source of current, means at said stations for variably applying current from said source to said line wires, a pair of local wires at one station, means at said one station for energizing one or the other of said local wires in accordance with current in one line wire, a second pair of local wires, means at said one station for energizing one or the other of said second pair of local wires in accordance with current in another line wire, and a receiving ele-

ment at said one station responsive only to one combination of energized wires in the first and second pairs.

41. In combination, a line circuit having a series of time spaced polar impulses impressed thereon, a polar line relay responsive to said polar impulses, a line repeating relay controlled by said polar line relay for repeating each of said impulses and each of said time spaces irrespective of the polarity of said impulses, a slow acting relay picked up on the first impulse of said series and dropped after the last impulse of said series, a plurality of stepping relays having pick-up circuits each including a front contact of the next preceding stepping relay, a half step relay for alternately preparing the pick-up circuits of the odd numbered and even numbered stepping relays, means including said line repeating relay for actuating said half step relay to an opposite position in response to each impulse on said line circuit, means including said line repeating relay and said half step relay for energizing the pick-up circuits of said stepping relays sequentially, one for each time space on said line circuit, and stick circuits for said stepping relays including a front contact on said slow acting relay.
- 10 42. In a remote control system, a line circuit having a series of time spaced distinctive polar impulses on said line circuit to characterize a code, a polarized line relay at said station distinctively responsive to all impulses of a series, a plurality of stepping relays and a single half step relay at said station, means controlled by said polar line relay so as to be responsive to each time space between successive impulses of a series for causing a separate one of said stepping relays to operate, means controlled by said polar line relay so as to be responsive to each impulse of a series for causing said half step relay to be actuated to an opposite position, means controlled by said half step relay and an operated stepping relay for selecting the circuit of the next stepping relay to be operated, means responsive to the operation of said stepping relays for sequentially selecting a series of local channel circuits, and means controlled by the distinctive operation of said polarized line relay following each operation of a stepping relay for energizing a channel circuit selected by the preceding stepping relay.

NEIL D. PRESTON.
